ENGINE

Carl F. Bachle, Detroit, Mich., assignor to Continental Motors Corporation, Detroit, Mich., a corporation of Virginia

Application October 7, 1931, Serial No. 567,379

6 Claims. (Cl. 123—52)

This invention relates to internal combustion engines and refers more particularly to an improved fuel mixture distributing means for such engines.

- 5 I find that although my improved fuel mixture distributing means is well adapted for use with engines in general, such as the poppet valve type, my invention has particular significance with engines of the sleeve valve type.
- 10 In engines and particularly in the sleeve valve type of engine it is customary to provide each cylinder with a plurality of spaced intake ports and such an arrangement gives rise to difficulties in efficiently distributing the fuel mixture to the ports, especially with the usual fuel mixture supply means.

It is an object of my invention to overcome the aforesaid difficulties by providing a fuel mixture supply means which will efficiently distribute the fuel mixture to the various cylinders of the engine and to the ports of each cylinder.

Further objects and advantages of my invention will be apparent as the description of my invention progresses, reference being made to the accompanying drawing illustrating one embodiment of my invention in which:

Fig. 1 is a fragmentary side elevation view of the engine showing my fuel mixture supply means partly in section,

30 Fig. 2 is a vertical transverse sectional view along the line 2—2 of Fig. 1,

Fig. 3 is a detail transverse sectional view taken substantially on the line 3—3 of Fig. 1, and

35 Fig. 4 is a detail sectional view of a one piece cast manifold structure of modified construction.

Referring to the drawing, reference character A represents an internal combustion engine of the sleeve valve type, the particular engine shown for illustration being of the single sleeve type 40 wherein each sleeve 10 is given a combined reciprocation and oscillation with respect to the cylinder and sleeve axes by any well known operating means.

The engine A has a plurality of cylinders 11 each provided with one or more exhaust ports 12 and a plurality of intake ports 13, these cylinder ports being controlled by the sleeve intake and exhaust ports 14 and 15 respectively. The cylinder block is provided with an intake 16 for each intake chamber 17 which extends around a portion of the associated cylinder whereby the cylinder intake ports 13 are open to the chamber 17 which in turn is open to the chamber intake 16 at the side of the cylinder block or engine A.

55 Each cylinder is provided with a suitable cyl-

inder head 18 and associated spark plug 19, piston 20 and connecting rod 21 these parts being well understood in the art and forming no part of my invention in themselves. The engine cylinders are exhausted by ports 15, 12 and exhaust 60 manifold 22.

My improved fuel mixture supply means consists, in the present embodiment, of a continuous intake manifold structure B having a riser 23 communicating with a carburetor 24 herein illustrated as the down draft type although the more common up draft type or other types may be employed if desired.

The manifold structure B is preferably constructed of primary and secondary sections C and 70 D respectively which are separated longitudinally by a partition 25, said sections and intermediate partition preferably secured together by bolts or other fastening means 26 and cooperating to provide primary and secondary fuel distributing 75 chambers or headers 27 and 28 extending generally parallel to each other, the secondary header 28 having port runner portions 29 adapted for registration with the various chamber intakes 16. The port runner portions are preferably located 80 generally below the secondary header 28.

It may be noted that the secondary header 28 is preferably located beneath the primary header 27, in order to obtain proper distribution of the wet fuel mixture, and said headers are preferably arranged to communicate as will be hereinafter described. The location of the communicating openings intermediate the headers may be best determined by experiment whereby to balance the pressures at the outlets for obtaining the desired uniform distribution of the fuel mixture as well as the wet fuel precipitates that are deposited on the partition 25 forming the floor of the header 27. It may be noted that the fuel is thus passed generally downwardly from the primary header 90 or conduit 27 to the port runners 29 which in the present embodiment of the invention communicate with a secondary header 28 that connects said conduit outlets with the port runners.

The intermediate partition 25 is preferably provided with holes 30 adjacent both ends providing passages for connecting the headers 27 and 28, and said partition is also preferably provided with a transverse hole or passage 31 located substantially at the middle of the manifold directly below 105 the outlet of the riser 23 for a purpose hereinafter made more apparent.

It will be observed that when a cylinder is drawing in fuel mixture, the fuel mixture is supplied from opposite directions in header 28 as 110

shown by the arrows 32 thereby causing the fuel mixture to pass substantially symmetrically or uniformly into the intake chamber 17. However, in testing a manifold of this type having only passages or holes 30, it was noticed that the middle cylinders were starved. In order to remedy this condition and to provide a uniform distribution of the fuel mixture to the several cylinders I employed one or more holes or passages 31 or 31' intermediate the holes or passages 30. The size of the hole or holes 31 or 31' was determined to be in general of less cross-sectional area than the holes or passages 30. Thus, the middle cylinders were supplied with fuel mixture sufficient to prevent the same from being starved.

In the preferred construction as illustrated by Fig. 1, I found that a single hole 31 opposite the outlet of the riser 23 provided a very satisfactory distribution of the fuel mixture, though a construction as illustrated by Fig. 4 having a plurality of holes or passages 31' intermediate the passages 30 and arranged substantially as shown in Fig. 4 produced satisfactory results. Obviously, it will be understood that one or more passages may be employed for placing the headers 27 and 28 in communication at points intermediate the communicating passages at or near the ends of the manifold structure.

It will probably be desirable to construct the manifold of a single casting as illustrated in Fig. 4 instead of providing a separate partition wall and the holes or passages in the partition may be cast or drilled as desired. Furthermore, I find it quite desirable in many instances to arrange the passages connecting the headers 27 and 28 symmetrical about the center of the manifold structure. It will be noted that these passages as shown in Fig. 4 are arranged symmetrical about the transverse plane containing the axis of the riser 23 as is the case with the passages shown in Fig. 1. It will be understood, however, that I do not limit myself to such a symmetrical arrangement since in some instances I may desire to provide an unsymmetrical arrangement.

The herein described structure provides an intake manifold substantially of the trombone type and it will be noted that the horizontally extending headers 27 and 28 are substantially parallel and have a common intermediate wall provided with one or more holes or passages for providing intercommunication between the headers in order to supply substantially uniform distribution of the fuel mixture to the engine cylinders.

Preferably, the partition wall which forms the floor of the primary header 27 is provided with a shallow groove or depression 35 extending longitudinally of the header and serves to assist in the wet fuel mixture distribution.

It will be thus noted that my improved fuel mixture distributing means provides for uniform distribution to the engine cylinders, said means providing improved engine performance for engines having individual or separate means for conducting the fuel mixture to each cylinder. Such an arrangement as heretofore described may be efficiently utilized in sleeve valve engines where individual fuel mixture inlets for each cylinder are quite desirable, and therefore though my invention has particular significance with sleeve valve engines I do not necessarily limit my invention in its broad aspects to use with a sleeve valve engine, since the principles of my

invention may be embodied in engines other than those of the sleeve valve type.

It will be apparent to those skilled in the art to which my invention pertains that various modifications and changes may be made therein without departing from the spirit of my invention or from the scope of the appended claims.

What I claim as my invention is:

1. In an engine of the type having a plurality of cylinders each provided with an intake port and having valve means associated therewith, a fuel mixture conducting manifold structure having a primary header and a secondary header, the latter extending generally longitudinally of the engine and communicating with said intake ports, said headers having a common intermediate wall separating same and provided with passages for connecting the end portions of said headers, said wall having one or more passages for connecting said headers intermediate the end portions and provided with a groove extending longitudinally along the floor of the primary header.

2. In an engine of the type having a plurality of cylinders, a fuel mixture conducting manifold structure having a fuel distributing conduit provided with one or more openings in the bottom floor thereof and intermediate the ends thereof through which to distribute fuel mixture by gravity to said cylinders.

3. An intake manifold structure for a multi-cylinder engine including a fuel mixture conducting riser, a fuel distributing conduit communicating with said riser and having one or more openings in the floor thereof and intermediate the ends thereof for passing fuel generally downwardly to said engine cylinders.

4. An intake manifold structure for a multi-cylinder engine including a fuel mixture conducting riser, a fuel distributing conduit communicating therewith and extending generally longitudinally of the engine, said conduit having spaced graduated openings in the floor thereof for metering and passing fuel generally downwardly to said engine cylinders.

5. An intake manifold structure for a multi-cylinder engine including a fuel mixture conducting riser, a fuel distributing conduit communicating therewith and extending generally longitudinally of the engine, port runners individually communicating with the engine cylinders and extending generally transverse to said conduit, and means intermediate the port runners and conduit and including one or more openings in the floor of the conduit intermediate the length of said conduit for conducting fuel generally downwardly from said conduit to the engine cylinders.

6. An intake manifold structure for a multi-cylinder engine including a fuel mixture conducting riser, a fuel distributing conduit communicating therewith and extending generally longitudinally of the engine, port runners individually communicating with the engine cylinders respectively and extending generally transverse to said conduit, and means intermediate the port runners and conduit and including one or more openings in the floor of the conduit spaced longitudinally between the ends thereof for conducting fuel generally downwardly from said conduit toward the engine cylinders.

CARL F. BACHLE.
